UNITED STATES PATENT OFFICE

132,211

DESIGN FOR A UTILITY TRUCK

Oscar Raymond Peterson, Tournapull, Ga.,
assignor to R. G. Le Tourneau, Inc., a corporation

Application October 10, 1941, Serial No. 103,708

Term of patent 14 years

To all whom it may concern:

Be it known that I, Oscar Raymond Peterson, a citizen of the United States, residing at Tournapull, in the county of Stephens and State of Georgia, have invented a new, original, and ornamental Design for Utility Truck, of which the following is a specification, reference being had to the accompanying drawings, forming a part thereof.

In the drawings:

Figure 1 is a side perspective view of a utility truck, looking toward the rear and showing my new design;

Figure 2 is a side elevational view of the utility truck;

Figure 3 is a rear elevational view of the utility truck, and

Figure 4 is a perspective view of the utility truck, looking toward the front from the side opposite that shown in Fig. 1.

I claim:

The ornamental design for a utility truck, as shown.

OSCAR RAYMOND PETERSON.
